UNITED STATES PATENT OFFICE.

ROBERT B. CRAIG AND ALBERT L. COFFMAN, OF GRAND RAPIDS, MICHIGAN, ASSIGNEES
TO CHAMPION RECORDING MACHINE COMPANY, A CORPORATION OF SOUTH
DAKOTA.

TRANSFER PRINTING AND ISSUING MACHINE.

1,280,966.

Specification of Letters Patent.

Patented Oct. 8, 1918.

Application filed December 10, 1913. Serial No. 805,680.

To all whom it may concern:

Be it known that we, ROBERT B. CRAIG and ALBERT L. COFFMAN, citizens of the United States, and residents of the city of Grand Rapids, county of Kent, and State of Michigan, have invented certain new and useful Improvements in Transfer Printing and Issuing Machines; and we do hereby declare that the following is a full, clear, and exact description of the same, reference being had to the accompanying drawings, and to the numerals of reference marked thereon, which form a part of this specification.

15 In the operation of street railways, including some suburban lines, and also certain boat lines, a transfer slip issued by another carrier or a branch of the same carrier, is receivable for transportation, and the conductors or fare collectors are required to carry quantities of such transfers to be punched upon delivery to the passenger and to be used in payment of the fare on a related connecting carrier.

20 It is a usual requirement to punch or mark the approximate time of delivery of the transfer to the passenger, supposedly for the purpose of enabling the collector for the connecting carrier to determine the

25 validity of the transfer for a continuous passage. Uncertainty has heretofore always existed, however, both in the mind of the collector as to the accurate marking of such transfer slips, inasmuch as the issuing

30 conductor or collector frequently marks the same in large quantities, and delivers them from time to time to passengers, as required, so that the hour punched very frequently does not agree with the hour presented to the collector of the connecting carrier, even though immediately presented. In consequence, frequent disputes arise, and sometimes litigation.

35 Considerable loss is also entailed from the issuing conductor losing such transfers, the finder sometimes using the same for passage and without the payment of fare. It has also been a serious cause of objection to the use of such transfers, that the time

40 consumed in punching or marking the trans-

fers is so great as to seriously interfere with the other duties of the collector.

It is an object of this invention to afford an automatically acting transfer issuing machine, from which the transfers are delivered, correctly dated and marked with the day and hour, and also the intersecting line with which the same is to be used, and serially numbered, thus enabling the passenger entitled to the same to be given a correctly marked transfer without delay, and enabling the collector to determine at a glance, with certainty, if the transfer presented is, in fact, tendered for a continuous passage.

45 It is also an object of the invention to afford in a machine of the class described, automatic printing and timing mechanism, and mechanism for guiding the transfer slip correctly to the printing means to insure accuracy of registering and correct printing.

50 It is a further object of the invention to afford a device embracing means for correctly registering the transfer slip with the printing means, and also means for severing the individual transfers from a continuous strip after the same have been printed.

55 It is an object of the invention to afford a novel dating and timing mechanism, insuring accuracy of the data impressed upon the transfer.

60 It is also an object of the invention to afford a construction in which the timing and dating mechanism act continuously and automatically to change the dating of the machine from day to day, and to afford mechanism in connection therewith whereby correct dating is assured for a period of years, including leap years.

65 It is an important object of the invention to afford means for indicating the transfer point on such transfer, and the line by which the transfer is issued, and also the direction of transfer of the carrier from which issued.

70 It is a further and important object of the invention to provide an exceedingly strong and durable device of the class described, in which the mechanism is at all

with downwardly directed peripheral flanges 2 and 3, is mounted upon a casing 4, of sheet metal affording a lower compartment for the machine, said casing fitting within 5 the downwardly directed flange 3, of the base plate, and a similar casing or shell 5, of sheet metal or other suitable material, is engaged at its lower open end within the upwardly directed flanges 2, of the base 10 plate, and affords an upper compartment or chamber housing the operating mechanism of the machine.

Mounted upon the base plate and rigidly secured thereto at the lower ends thereof, 15 near opposite sides of the same, are upright parallel frame plates 6 and 7. Connecting said plates at their top, is a frame bar 8, which acts, together with said base, to hold said frame members 6 and 7, in unvarying 20 relation. As shown also, a horizontal frame bar 9, is rigidly secured to said frame plates 6 and 7, at corresponding edges of said frame plates, as shown in Figs. 5 and 9, and the lower edge thereof is shaped to afford 25 one member of the cutting mechanism for severing the transfers from the strip as hereinafter more fully described. Said bar 9, also serves to increase rigidity of the frame.

Journaled upon a suitable spindle 10, carried upon the bracket 11, in the lower compartment of the frame, is a paper roll 12, comprising a strip of paper or other suitable material of a width suitable for one dimension of the transfer; for example, the 30 width thereof may correspond with the length of the transfer when issued, as illustrated in Fig. 43, and said strip, as shown, is provided with closely arranged perforations arranged in parallel lines transversely 35 of the strip and equal distances apart, the distance apart corresponding with the other dimension of the transfer when issued, for example, the width thereof. The end of the transfer strip is trained about a suitable resilient tension device 13, and thence upwardly, into the upper compartment.

Rotatably secured between the frame plates 6 and 7, on a shaft 14, is a drum or roll 15, the axis of which extends transversely of the strip 12. Set in the periphery 40 of said roll, and arranged in longitudinally extending lines a distance apart to correspond with the distance between adjacent lines of perforations in the strip, are pins 16, which engage in the perforations in said strip and act to insure accuracy of feed, as hereinafter more fully described. From said roll 15, the strip is led outwardly and substantially horizontally by means of suitable 45 feed rolls 17 and 18, which pass the end of the strip beneath the frame or knife bar 9, and into position to be severed by the upward swing of the lower knife bar 19, as hereinafter more fully described.

50 Set in the front wall at the top of the

upper casing member 5, is a clock mechanism, the dial 20, of which is exposed to view at the outer side of the casing. The shaft 21, for the minute hand, projects rearwardly from the clock mechanism, and the 55 end thereof is journaled on the wall of the frame plate 7, as shown in Fig. 6, and rigidly secured thereon is a gear wheel 22, which meshes with a larger gear wheel 23, journaled on said frame plate. A pinion 24, 60 which meshes with the gear wheel 23, is yieldingly engaged upon a short shaft section 25, journaled in the frame plate 7, and rigidly secured on said shaft section 25, at the inner side of said frame plate, is a minute wheel 26, having marked on its periphery, as shown at A, in Fig. 10, the numerals beginning with 1, and ending with 58, indicating the minutes by threes successively.

Journaled in the frame plate 6, and in the bore of the minute wheel 26, in alinement with the shaft section 25, is a shaft 27, and journaled thereon are indicating wheels of uniform diameter with the minute wheel 26, and in their order arranged as follows (Figs. 90 10 and 18): 28, indicating hours; 29, indicating the days of the month consecutively; 30, indicating months; 31, indicating the number of the year; 32, indicating direction, and 33, indicating streets, the peripheries of 95 said wheels being marked appropriately, as indicated at Fig. 10, in which an appropriate reading for each wheel is shown at A, B, C, D, E, F, and G, respectively. As shown, the wheel 32, indicating direction, is rigidly 100 keyed on the shaft 27, and on the outer end of said shaft where the same extends through the casing 5, is secured a crank 34, provided with a suitable handle 35. Concentric with 105 said shaft, and secured to the outer wall of the casing, is a dial 36, shown in Fig. 2, and marked to indicate the directions, and said direction indicating wheel 32, is secured on said shaft to correspond with the pointer or crank arm 34, so that when the crank arm is 110 adjusted as a pointer to any of the markings on its adjacent dial, the direction indicated on the dial is likewise indicated at the under side of the periphery of the direction wheel 32, in position for printing.

A gear wheel 37, is rigidly secured on one end of the street indicating wheel 33, as shown in Figs. 9 and 18, and journaled above the same on the frame plate 6, is a shaft 120 having rigidly secured thereon a gear wheel 38, meshing with the gear wheel 37, and provided on its inner end with a bevel gear 39, which meshes with a bevel gear 40, secured on a shaft 41, which extends through the top of the upper casing, as shown in 125 Figs. 4 and 9.

Surrounding said shaft 41, is a clamping ring 42, having an inwardly projecting flange at its inner periphery, adapted to engage over and clamp in place an indicating 130

disk or dial 43, marked with the streets of the street railway (or other) system, upon which the device is to be used, and a glass cover plate 43^a, therefor, as shown in dotted lines in Fig. 7.

Rigidly secured on the upper end of said shaft 41, is a crank 44, provided with an operating handle 45, to permit the same to be used in rotating the shaft and consequently 10 the street indicating wheel. As shown, the crank arm at its outer end is reversely bent, the extremity thereof affording a pointer adapted to indicate the desired street upon the dial, said crank being so set upon said 15 shaft that the street name corresponding with the dial indication is in printing position on the street wheel; that is to say, at the under side the periphery thereof.

As shown, and preferably, the clamping 20 ring 42, is provided with an aperture in its face, opposite each of the street names indicated thereon, and the handle 45, for the crank in that event is constructed to afford a spring pressed pin or detent adapted 25 when released, to engage in the respective apertures in the clamping ring with the inturned pointed end of the lever 44, directed toward the required direction printed upon the dial. The detent acts to 30 hold the indicating lever from movement whether occasioned by the vibration due to the travel of the car or from accidental causes, but permits quick release for adjustment to another car or line of the same system when desired, which is clearly indicated 35 in Fig. 4.

Each of the time indicating wheels 26, 28, 29, 30 and 31 are provided on one end thereof with double ratchet teeth spaced equal 40 distances apart, said ratchet teeth being provided integrally on the ends of said wheels, as shown, though, of course, if preferred, the same may be constructed separately and secured in any suitable manner to the respective wheel. The ratchet teeth for the 45 minute wheel, as shown in Fig. 11, are indicated by 47, and that for the hour wheel, as shown in Fig. 12, by 48. A shaft 46, is secured in said frame plates 6 and 7, adjacent the periphery of said wheels, and parallel the shaft 25—27. Rotatably secured on 50 said shaft, with the periphery thereof projecting between adjacent printing wheels, is a mutilated gear wheel 49.

55 A mutilated pinion 50, is provided on the inner end of the hub of the minute wheel in position to mesh with the teeth on said gear 49, so that as the minute wheel is rotated by the clock, the mutilated gear 49, is thereby 60 rotated by being driven by said mutilated pinion. Pivotaly engaged upon said mutilated gear above and adjacent to the shaft 46, is a pawl 51, which rests upon the ratchet teeth 48, of the hour wheel, and as the mutilated gear is rotated by the pinion on the 65

minute wheel, is projected forwardly a distance equal to one tooth of the ratchet 48, to engage the next succeeding tooth. As shown, a spring 52, is engaged upon a suitable shaft 53, engaged in the frame plates 70 and extends forwardly and bears lightly upon said pawl 51, and is looped at its free extremity, a pin 54, set transversely in the head of said pawl extending into the loop, so that the spring arm 52, may be 75 utilized to raise the pawls, if desired, by means of said pins.

A transversely slotted bar 55, is supported on the frame plates, the slots therein being positioned to receive the periphery of the 80 mutilated gears therein, and a stop pin 56, set in said gear wheel, as shown in Fig. 12, acting to limit the reverse rotation of said gear wheel when released. A strong pulling spring 57, is engaged at one end on said 85 mutilated gear and at the other on a suitable pin or shaft 58, extending between the frame plates, and acts normally to hold the gear in reverse position or with the stop 56, bearing upon the upper surface of the slotted plate 55.

Secured also on said shaft 58, is a pulling spring 59, which engages an arm 60, of a pawl 61, the other end of which projects beneath the hour wheel into position to engage the ratchet teeth thereof near the under side of the wheel. This arrangement insures a sufficient rotation of the mutilated gear wheel 49, to cause a forward projection of the pawl 53, to engage the next succeeding gear 100 so that at the moment the continued rotation of the mutilated pinion brings the same out of mesh with the mutilated gear, that is to say, at the end of one complete rotation of the minute printing wheel, the pull of the 105 spring 57, reverses the motion of the mutilated gear wheel 49, turning the hour wheel one notch, the pawl 61, coöperating with the pawl 51, to hold the hour printing wheel in printing position until again actuated for 110 the next succeeding hour.

As shown also, a detent 62, is pivotally supported on a shaft 63, which is secured on the frame plates and extends alongside the printing wheels, one of said detents being 115 provided for each of the time indicating wheels. Said detent is provided with a projection 64, which extends over the head of the pawl 51, to permit said detent to be lifted out of engagement with its ratchet 120 tooth with the forward movement of said pawl, but otherwise at all times said detent, is held in engagement by means of a pulling spring 65, engaged thereto and upon any fixed point upon the mechanism.

125 As shown, the hour wheel is marked to indicate twenty four hours, the first series of numerals from 1 to 12, being marked "A. M." and the second series of numerals from 1 to 12, being marked "P. M." to indicate 130

the hour of the day correctly upon the printed slip, as hereinafter described.

The next succeeding printing wheel or that marked 29, and appropriated to the 5 days of the month, is actuated successively by each rotation of the hour wheel to move one notch, or, in other words, to indicate one day additional with each such movement, and with each complete rotation of said 10 wheel the month's wheel 30, is actuated to set the same to print the name or abbreviation for the next succeeding month. Inasmuch as the number of days in the different months of the year vary, the month of February having twenty eight or twenty nine days, and other months having thirty or thirty one days, it is desirable to so adjust and construct the machine as to enable it to continuously and correctly mark or print 15 the date without the necessity of changing it or resetting it for each month or for leap years.

Extending parallel the shaft 63, and capable of a slight longitudinal movement, is a 20 shaft 66, over which the detents 62, extend, as shown, and rigidly secured on said shaft 66, and projecting at its periphery between the hour printing wheel and the days printing wheel, is a disk 67, and similarly secured 25 on said shaft and projecting between the months and years printing wheels, is a disk 68, as shown in Fig. 9. The end of the day printing roll 29, directed toward the hour printing roll 28, is provided concentrically 30 with radially directed teeth or projections 69, as shown thirty one in number, corresponding with the largest number of days possible in a month, and three of these projections, as shown in Fig. 13, consecutively 35 arranged, are stepped or notched, as indicated at 70, 71 and 72, in Fig. 20, and as shown also in Fig. 13, to enable the machine to print correctly the number of days for the 40 respective months, and a 29th day in February for leap years, as hereinafter more fully described.

The mutilated gear wheel 49^a, for said days printing wheel, is constructed as before described, and is journaled on the shaft 45 50 46, as shown in Fig. 13, and the pawl and detent 73, is pivoted thereon, as before described with reference to the pawl 51, secured on the mutilated gear wheel 49, and projects over said printing wheel, and rests 55 on the radial teeth 69 to 72 inclusive.

Similarly, a mutilated pinion 74, is provided on the hub of the hours wheel 28, and meshes with the teeth of the mutilated gear 49^a so that a complete rotation of the wheel 60 indicating twenty four hours, acts to rotate the days wheel one notch to indicate the next succeeding day, and this will be continued, of course, successively for the entire month.

The wheel for months, as hereinafter described, is actuated from the days wheel to

rotate one space or to set up the next succeeding month in the printing position at the completion of each rotation of the days wheel. To insure the automatic adjustment of the months wheel to the days wheel, 70 and to insure the appropriate number of days in each month to be printed and neither more nor less, the pawl 75, is pivotally supported on the shaft 63, at its lower end and extends upwardly and over the geared or 75 toothed hub of the days printing wheel in position to engage the same, as shown in Figs. 13 and 20, and lies in close proximity with the pawl 73, the downturned free extremity of which projects behind a roller 76, 80 journaled on said pawl 75, so that in raising the pawl 73, the pawl 75, of necessity must follow, clearing the teeth on the days wheel.

As shown, a pulling spring 77, is engaged upon a pin 78, on the detent 75, and with 85 the fixed part on the frame, and acts normally to hold said detent in engagement with said teeth.

As shown, the machine is so constructed that it will print accurately the appropriate 90 number of days for each of the calendar months counting twenty eight days for February in ordinary years and twenty nine days for February in leap years. For this purpose, mechanism is provided whereby the 95 months wheel will not be shifted or actuated until the number of teeth on the days wheel 29, corresponding with the number of days for the respective months, have been engaged by their detents. For this purpose, 100 as shown, the printing wheel 30, for months, is provided on its end adjacent the wheel 29, for days, with ratchet teeth 78, as shown in Figs. 14 and 44. These are arranged to correspond with the respective months on 105 the months wheel, and the depth of the throat of which vary with the number of days in each month—that is to say, for months having thirty one days, the throat for said teeth are deepest; for months having thirty days, of less depth, and for the month of February, as shown in Fig. 44, Sheet 12 having a shallow throat 79, for those years in which February has but twenty eight days, and a deeper throat or 110 115 portion of the throat 80, adjacent thereto for leap years when February has twenty nine days. As shown, in Fig. 38, the deeper throat or portion of the throat for the month of February is arranged nearer the 120 outer face of said ratchet wheel affording a stepped throat for the February ratchet tooth.

Secured on the detent 75, at its side adjacent to, and projecting toward the months 125 wheel, is an arm 81, carrying a fixed detent 82, as shown in dotted lines in Fig. 13, and full lines in Figs. 14 and 38, said detent projecting into position to engage the ratchet teeth of the ratcheted end of the hub 78, of 130

the months wheel 30, and means are provided for shifting said detents 75, and, of course, the detent 82, therewith, to enable said detent 82, to project into the deeper 5 throat during the month of February at each leap year. For this purpose, as shown, the shaft 63, has a spiral spring 83, wound thereon, as shown adjacent the days wheel, which bears against a grooved collar 84, slideable 10 on shaft 63, and into which the disk 67, on the shaft 66, projects at its periphery. The disk 68, also rigidly secured on the shaft 66, is convex on its face adjacent the year wheel 31, and set in the face of said year wheel adjacent 15 said disk 68, and corresponding in position with each of the leap years which may be marked upon said wheel, is a pin 85, as shown in Figs. 15 and 39, so that on leap years, said pins engaging with the disk 68, 20 throws the shaft 66, bodily longitudinally against the tension of the spring 83, carrying the detent 75, that is secured to the collar 84, therewith, and thereby positioning the detent 82, to engage in the deeper throat 25 of the February ratchet tooth.

As shown, a bent lever is fulcrumed on the shaft 86, on which also is fulcrumed the detent lever 61, before described, and one end 87, of said lever is engaged by means of a 30 pulling spring 88, with the shaft or rod 58. The other arm 89, extends upwardly and rearwardly alongside the radial teeth on the days wheel, and is provided at its upper end with a laterally directed pin which may 35 carry a roller, as shown in dotted lines in Fig. 13. Secured on the end of the days wheel beneath the pin or roller on the arm 89, of said lever, is a cam 90, having a relatively long throw and so secured on said 40 days wheel as to elevate said lever arm 89, against the tension of its spring as the day wheel is rotated.

It is to be noted that on the opposite end of the days wheel is a mutilated pinion 45 driven by a mutilated gear 49^b, as before described with reference to the other printing wheels, said mutilated gear 49^b, having secured thereon a pawl 53^b, similar to the pawl shown in Fig. 3, and before described, 50 and similarly engaging the teeth of an inner ratchet 91, on the months wheel. As shown in Fig. 14, a pawl 62^b, (which may be identical with the pawl 62, before described with reference to the hour wheel) is pivotally supported on the shaft 63, normally held in engagement by means of the spring 65^b, and is adapted to be lifted and released by the forward movement of said pawl 53^b, so that with each rotation of the days wheel 29, the 55 month wheel 30, is rotated one station or to 60 set up the next succeeding month in printing position.

In a similar manner a mutilated pinion is secured on the end or hub of the month wheel 30, adjacent the year wheel 31, and is

engaged and meshes with the teeth of a mutilated gear wheel 49, rotative on the shaft 46, and carrying a pinion 53, as before described, and controlled by a pawl 62, corresponding with the pawl 62, before described, 70 and adapted to be lifted by the movement of the pawl 53, and adapted to be reversed by a pulling spring 57.

The operation of the day, month and year wheels is as follows: The day wheel is rotated a distance equal to one tooth or one space with each rotation of the hour wheel and will continue until the number of days has been indicated or adjusted in printing position on the day wheel corresponding therewith in printing position on the month wheel and in the throat of the ratchet teeth for which the detent 82, is engaged. If said tooth is engaged in one of the deep throats for a month having thirty one days, the detent 75, held inwardly by its spring 77, will engage each of the teeth in succession, including the relatively low teeth 70, 71 and 72, on said day wheel and will release only when the movement of the pawl 73, over the 90 day wheel, has progressed far enough to raise the detent 75, similarly as before described with the release of the hour wheel, permitting the wheel to be turned to present another day number in printing position. 95

For months having but thirty days, the ratchet throats on the ratcheted end 78, of the month wheel are shallower, thereby supporting the pawl 75, sufficiently high to clear the radial tooth 72, thus stopping the day 100 wheel in position for the numeral 30 to be in printing position. At this time the cam 90, supports the lever arm 89, against the tension of the spring 88, so that with the next release or that at the end of the day 30, the 105 printing wheel turns two notches under the coaction of said cam and lever, again restoring the day wheel in position to print the numeral 1.

In a similar manner for Februaries having 110 but twenty eight days, the detent 82, is supported in the shallowest February throat or that indicated by 79, and in consequence supports the detent 75, in position to clear the radial teeth 71 and 72, on the end of the 115 printing wheel, so that at the end of the twenty-eighth day the coaction of said cam 90, and lever arm 89, under the influence of the spring 88, causes the day wheel to rotate freely for three teeth, bringing the wheel 120 back into position to print the numeral 1, for the next succeeding month.

With leap years, said detent 82, in the month of February, engages in the deeper February throat, as indicated in Figs. 38 125 and 44, having been forced to that position by the engagement of one of the leap year pins 85, mounted on the year wheel 31, adjacent the position of every fourth or leap year, against the rounded disk 68, on the 130

shaft 66. In this position all the days count to twenty nine inclusive, and the detent 75, being supported sufficiently high to clear the thirtieth and thirty first teeth, the printing 5 wheel again returns to normal or to print the numeral 1.

Of course, with each complete rotation of the day wheel, the month wheel is actuated one station or to indicate the next succeeding 10 month. With each rotation of the month wheel the year wheel is rotated to indicate the next-succeeding year, and it is obvious that in this manner, the correct date will always be presented in printing position even 15 for a long term of years, including the hour and approximately the time in minutes so long as the clock continues to run accurately. Conveniently, the minute wheel is arranged in three minute spaces, and it is for this 20 reason that the actuating gear wheel 24, on the end of the shaft 25, is loosely engaged thereon to prevent any undue stress being exerted on the clock or other mechanism.

As shown, said gear wheel is loosely engaged on said shaft and a coiled spring 93, is engaged at one of its ends to the gear wheel and at its other end to a pin 94, extending through the shaft and collar therefor to permit relative movement of the shaft 30 and gear wheel sufficient to permit the parts to compensate. Pawls other than those before described, are not essential, for either the street wheel or direction wheel, inasmuch as the one is held in adjusted position 35 by its bevel gear wheels, whereby the same is driven, and the other by the spring detent 45, before described. If preferred, however, a spring controlled detent 95, may be secured upon the shaft 86, as before 40 described, with reference to certain other detents, and may engage a suitable ratcheted hub 96, on one side of the direction wheel.

The tape or transfer strip 42, of paper or other material, feeds transversely the printing 45 wheels beneath the same, and the printing position on each wheel is at the under side of the wheel, as shown in Fig. 7. Extending transversely the transfer tape and between the same and the printing wheels, is 50 an inked ribbon such as a typewriter ribbon, indicated by 97, wound at each of its ends about suitable mechanically driven and automatically reversible ribbon spools. Said ribbon spools may be supported upon any 55 suitable portion of the frame, but, as shown, a bar or rail 98, is secured at its ends to the side frame plates 6 and 7, below and adjacent to the feed rolls 17 and 18, and is engaged in place by means of set screws 99, 60 which extend through the side plates 6 and 7, into the ends of said bar, as shown in Figs. 25 and 28, and, as shown, are provided each with a collar 100, adapted to be engaged by the head of a screw 101, set adjacent thereto 65 in the side frame plate and acting to pre-

vent the removal of the set screws without first removing the adjacent screws 101.

A stud shaft 102, is secured on the bar or plate 98, adjacent each end thereof at each side of the transfer strip and rotatably engaged on each is a ribbon spool 103, about which the inked ribbon 97, is oppositely wound. Secured near each end of said bar 98, is an upright 104, at the upper end of each of which is an inwardly extending horizontal rod 105, one at each side of the transfer strip and in the same plane therewith and over which the bight of the inked ribbon extends, as shown in Figs. 29 to 34 inclusive.

Journaled upon a central pivot pin 106, 80 secured centrally on the frame plate 98, is a lever 107, the ends of which, as shown, are of substantially equal length and at the outer ends of each of which is pivotally secured an upwardly and inwardly directed 85 pawl 108, either of which is adapted to engage a ratchet wheel 109, rigidly secured on the adjacent ribbon spool when the other end of the lever is elevated. A spring 110, engages the respective pawls with said lever 90 107, acting to hold the same inwardly each to bear against its ratchet wheel.

Pivottally secured on the lever 107, at the inner side of each of said ribbon spools, is an upwardly directed arm 111, provided 95 with a finger 112, extending upwardly therefrom and a pulling spring 113, is engaged on said lever 107, and the arm 111, and acts to hold said arm inwardly against the adjacent spool or the ribbon thereon. 100 As shown in Figs. 31 and 32, each of the spools is provided with a peripheral groove 114, with which the arm 111, registers to permit the arm to swing therewith under the draft of its spring when the last turn of the 105 ribbon is wound from the spool, thereby permitting the arm to swing sufficiently toward the spools for the finger 112, thereof to engage against a stop pin 115, secured in said plate or bar 98, thereby momentarily limiting the upward swing of that end of the 110 balance lever 107, to effect the shift of the feed of the ribbon.

This is accomplished as follows: The lower shaft 17^a, on which are the transfer 115 feed rolls 17, is provided with an eccentric 117, thereon, as shown in Fig. 34, and extending downwardly therefrom and engaged therewith is an eccentric rod 118, provided at one side with a spring 119, shaped at its 120 lower extremity to afford a V-shaped detent 120, which engages in one or the other of two notches 121, or 122, in the edge of an extension bar 123. Said extension bar is engaged by means of bolts 124, which extend through slotted apertures therein with the eccentric rod 118.

Secured on the lower end of the extension bar 124, in any suitable manner, is a stud 125, which projects inwardly through 130

a slot in the lower edge of the bar 98, in one end thereof, and is pivotally engaged on the balanced lever 107, as shown in Figs. 29 to 34 inclusive.

5 In operation the ribbon feed is continuously actuated by the rotation of the shaft 17^a, for the feed rolls, 17, the appropriate pawl 108, actuating the ribbon roll by engagement with its ratchet wheel with each 75 oscillation of the balanced lever 107, with both the arms 111, held inwardly so that the fingers 112, thereon cannot engage the stop pins 115, before described. This operation continues until one of said arms is permitted to swing into the groove in the ribbon 15 spool by the unwinding of the last turn of the ribbon thereon. This immediately permits the finger 112, to engage beneath the stop pin 115, so that the next rotation of the feed shaft 17^a, and its cam 117, thereon, acts to shift the adjustment of the spring 119, so that the detent 120, thereon, is removed 20 from engagement with the notch of the extension bar 24, with which formerly engaged, and engages in the adjacent notch, 25 thus shortening the connection between the stud 125, and the shaft 17^a, and acting to elevate the pawl previously actuating the ribbon roll beyond engagement, and to bring 30 the pawl 108, at the other end of the balanced lever, into position to engage its ratchet wheel 109, to rotate its ribbon spool, and, of course, oppositely from the rotation of that previously described. The ribbon spools are thus alternately driven to 35 wind the inked ribbon thereon.

The printing is effected by striking the transfer strip and ribbon upwardly against the printing wheels. For this purpose, a 40 U-frame 126, is pivotally supported in the machine beneath the printing rolls by means of screw bolts 127, which extend through the side frame members 6 and 7, and engage in the arms 128, thereof, which extend forwardly as shown in Figs. 7 and 8, at each 45 side of the machine beneath the transfer tape and inked ribbon. Said arms 128, are connected across their inner ends directly beneath the printing position on the printing wheels by a channelled bar 129, adapted 50 to receive therein a rubber or other strip 130, adapted to afford a striking member, whereby the transfer strip is driven against the ribbon and the latter against the printing faces on the printing wheels to print the data thereon, and, as shown, an inner channelled bar 131, is secured on said arms 128, at the inner side of the inner channelled bar 129, and is provided with a rubber or other 55 suitable striking face 132, engaged therein, as shown in Figs. 7 and 8, to enable other data to be printed upon the transfer strip than that printed by means of the printing wheels. For example, a channelled type bar 60 133, may be suitably secured on one of the

frame plates, for instance, 6, as shown in Figs. 7, 8, and 40, and may be provided in its under channelled face with rubber or other type 134, 135, to print on the transfer the name of the line and the number of 70 the machine, as shown in Figs. 41 and 43, in which the words "Broadway" indicates the line and the number "9999" indicates the number of the machine, the printing face in said bar being positioned at the same 75 level with the printing faces on the printing wheels to enable all to print simultaneously.

As shown, a strong leaf spring 136, is engaged centrally on the back bar 126 of said U shaped striking frame. For this purpose, an inner clamping bar 137, is engaged within the bar 126, between the arms 128, and bolts or set screws 138, extend through said bars 126, said springs 136, and the bar 137, and also the spacing blocks 138—139, and rigidly clamp all together. 80

Extending through slots in the side frame plates 6 and 7, concentric with the pivot screws 127, are gudgeons 140, 141, which are engaged in the respective arms 128, between the pivot pins 127, and the outer ends of said arms. Said gudgeons protrude beyond the arms of said side frame plates, and means are provided for actuating said yoke 95 by engagement with one or more of said gudgeons, as hereinafter more fully described.

All the mechanism, with the exception of the printing rolls, are operated by the attendant or collector by means of an operating handle 142. As shown, said handle is fulerumed on a suitable bearing 143, at the under side of the base plate 1, and projects forwardly and outwardly beyond the casting, as shown in Figs. 1 to 4, and 6, and is suitably connected to drive the feed rolls and other mechanisms. For this purpose, as shown, a shaft 144, is journaled transversely the end of the machine above said handle, 100 and is provided with a bevel pinion 145, rigidly secured thereon, which meshes with a bevel gear wheel 146, rigidly secured on the shaft 14, of the strip feeding roll 15. 105

Also secured on said shaft 144, is a bevel pinion 147, which meshes with a bevel pinion 148, secured upon a stud shaft fixed to the frame plate 7. The relatively long hub 149, of the pinion 148, is provided with a gear wheel or pinion 150, secured thereon, which meshes with a gear wheel 151, and secured upon a stud shaft 152, secured in said frame plate 7. Said gear wheel 151, meshes with the pinion 153, of the lower transfer ejecting shaft 17^a, and the pinion 153, meshes with a corresponding pinion 154, on the upper transfer ejecting shaft 18^a, so that the rotation of the strip feeding roll 15, actuates also the transfer ejecting or feed rolls 17 and 18, to eject the transfer to severing position 125.

- tion. At the outer end of said shaft is a gear wheel 155, which meshes with a pinion 156, journaled below the same and on which is secured a counterbalancing wheel 157.
- 5 Set in the outer face of the gear wheel 155, is a pin or roller 158, disposed near the periphery of said wheel and in position to engage the free projecting end of a pivoted knife bar 159, to actuate the knife. Said
- 10 knife bar, as shown, is fulcrumed on a pin or shaft 160, secured at the end of the stationary knife bar 9, remote from the shaft 144, and extends downwardly to a point below the lower edge of the stationary knife bar, as shown
- 15 in Fig. 5, and thence forwardly into position for the free extremity thereof to be engaged by said pin 158, thus forming a bent lever, the upper edge of which adjacent to the stationary knife bar 9, affording one of the
- 20 members of a shear to sever the transfers from the strip when protruded therethrough.
- Fulcrumed at the angle or bend of said knife bar 159, is a lever 161, which extends downwardly and normally lies against projecting pins or studs 162, 163, set in the edge of the frame plate 6, and a strong pulling spring 164, shown as a spiral spring, is adjustably secured at one end on a bracket 165, secured on the frame of the machine, and
- 25 at the other end is secured on an inwardly projecting arm 166, secured on said lever, and acts at all times to hold said lever firmly against the pins 62 and 63, thereby holding the movable cutting bar 159, down-
- 30 wardly below the cutting edge of the fixed cutting bar 9, so that the shear afforded by said bar is open to permit the transfer to be fed therethrough. The construction is such, however, that when the
- 35 extended end of the cutting bar 159, is forced downwardly by the rotation of the gear 155, in engagement with the pin 158, on the end of the cutting bar, the spring 164, is tensioned by the outward thrust of
- 40 the cutting bar 159, which acts as a lever of the second class to force the bar or lever 161, away from the pin 163, so that when the further rotation of the gear 155, carries the pin 158, clear of said cutting arm, the
- 45 recoil of the spring 164, acts to throw the cutting arm upwardly to sever the transfer strip, permitting the same to fall outwardly into the chute 167, in position to be accessible to the passenger or fare collector.
- 50 As shown, a leaf spring 168, is secured in position to be engaged by the pin 158, at the moment of the release of the knife bar 159, thereby. Said spring acts as a brake to hold said gear from throwing unduly upon
- 55 the release of the knife bar. This is also assisted by the balanced wheel before described.
- Operative connections between the lever and the shaft 144, through the medium of the shaft 14, are provided to operate the
- mechanism just described. For this purpose, a ratchet wheel 169, is secured on the hub of the gear wheel 146, as shown more plainly in Fig. 22. Said ratchet wheel, as shown, is provided with four rectangular notches or recesses in its periphery arranged ninety degrees apart, each of said notches or recesses affording oppositely disposed ratchet faces or teeth. Rotatably mounted upon the shaft 14, is a tripping lever 170, (Figs. 6 and 23) the inner lower end of which is engaged by a strong pulling spring 171, the lower end of which is fixed to a bracket 172, rigidly secured on the base frame. As shown, a stop pin 172^a, is set in the side frame plate 7, in position to be engaged by the upper end of the tripping lever, 170, to limit the swing thereof under the impulse or recoil of the spring.
- Pivoted on said tripping lever 170, is a pivoted arm 173, having on its outer face near its extremity an outwardly directed finger 174, shaped to engage in any of said notches in the ratchet wheel 169. The inner end of said lever is inclined or beveled to afford a cam face, and a pin 175, is set in the frame plate 7, in position to be engaged by said inclined end thereof and to retract the projection or finger 174, from engagement with the ratchet wheel shifting 95 the same therefrom against the tension of the pulling spring 176, whereby said pivoted arm 173, is connected on the tripping lever 170.
- Pivoted upon the frame plate 100 7, is a link or bar 177, and pivotally engaged on the otherwise free end thereof, is a link 178, the other end of which is pivotally engaged on a pawl carrying bar 179, rotatably mounted between the tripping bar or lever 105 and the ratchet wheel 169, and the end of which extends well beyond the periphery of the ratchet wheel. Fulcrumed thereon, as shown in Figs. 6 and 35, is a pawl 180, provided with a tail 181, directed at substantially a right angle therewith and normally impinging against a stop pin 182, which limits the inward movement of the pawl. A pulling spring 183, is engaged on the tail of the pawl and with the outer end of the 110 pawl bar acting to hold said pawl normally inward. The head of the pawl extends over and normally engages the finger 174, as shown in Fig. 6, at which time said finger is held retracted from the ratchet wheel.
- Pivotally engaged on the link 177, and extending upwardly to engage over the gudgeon 141, carried on the yoke or printing frame, is a hooked arm 184, which lies in the same plane with the tripping bar and is adapted to be retracted from engagement with the gudgeon 141, by the upward swing of the lower extremity of said tripping bar, as shown in Fig. 35. As shown, a strong pulling spring 185, is engaged at one end 115
- 120
- 125
- 130

on the link 177, and the other end on the hooked arm 184, holds the arm inwardly for the hook thereof to engage over said gudgeon, as shown in Figs. 6 and 35. A link 185^a, is secured on the link or bar 178, adjacent its connection with the link or toggle bar 177, and at its lower end is connected with the handle 142.

A strong pulling spring 186, is engaged 10 on the link or toggle bar 177, and at any fixed point on the frame plate 7, above the same, and acts to hold said toggle bars or links and the lever, elevated, as shown in Figs. 6 and 35. As shown also, a strong 15 leaf spring 187, is secured to the side frame plate 7, and projects inwardly and upwardly beneath the ratchet wheel 169, and the angular end 188, thereof engages in the lowermost of the notches in said ratchet 20 wheel and acts to hold said ratchet wheel from movement until positively actuated, and as shown, the tripping bar 170, is shaped at its lower side to afford a cam projecting beyond the periphery of the ratchet wheel, 25 so that the rotation of the tripping bar acts to retract and release the spring 187, from engagement with the ratchet wheel at the moment of the engagement of the pawl finger 174, in the next succeeding ratchet 30 notch or recess in the ratchet wheel. The operation of the driving means is as follows:—

The operator or collector, upon receiving the fare or prepayment, upon request for 35 a transfer or ticket, forces the handle 142, downwardly, thus carrying the toggle bars or links 177—178, downwardly, and by engagement of the hooked arm 184, with the gudgeon 141, on the printing frame, swinging said yoke or frame downwardly against the tension of its spring 136. Simultaneously the pawl bar 179, and tripping bar 170, are drawn forward by the link 178, because of the mutual engagement between the 40 pawl 180, and the finger 174, the downward movement of the lever causing a partial rotation of the pawl bar and tripping bar on the shaft 14, and around the ratchet wheel 169, the ratchet wheel meanwhile being held 45 from movement by the leaf spring 187. When the next succeeding notch in the ratchet wheel is reached, the finger 174, which has been riding on the periphery of the ratchet wheel, falls into said notch under 50 the draft of the spring 176, thereon, thereby and at the same moment, the head 188, of the leaf spring 187, is forced out of holding engagement with the lower notch in the ratchet wheel and the tail of the tripping 55 bar has retracted the hooked arm 184, from the gudgeon 141, so that upon release by the pawl 180, of the finger 174, the return movement of the tripping bar and the rotation of the ratchet wheel 169, a consequent rotation 60 of the strip feeding wheel 15, begins under

the draft of the spring 171. With the release, however, of the gudgeon 141, from the hooked arm 184, the printing frame under the recoil of its springs 136, throws violently upward, striking the transfer strip 70 and ribbon against the printing wheels to afford the impression, and immediately falls back to normal position, as shown in Fig. 6. The rotation of the strip feeding roll feeds up another transfer. This is assisted 75 by the feed ejecting rolls 17 and 18, which are positively driven through the medium of the shaft 144, actuated by the bevel gear wheel 146, to which the ratchet wheel is secured.

The gear wheels for the shear are timed so that at the moment that the strip feeds outwardly sufficiently to bring the next succeeding transfers perforations in line with the pin 158, the knife bar 159, is released, 80 causing the same to throw violently upward under the recoil or draft of its spring 146, severing the strip in the line of its perforations and permitting the completely printed transfer to fall into the chute.

As the strip feeding roll 15, rotates ninety degrees under the action of the mechanism hereinbefore described, the next succeeding pins 16, engage in the next succeeding 85 perforations in the strip, always exactly 90 positioning the transfer to be printed by the printing mechanisms before described, while the draft of the ejecting rolls maintains said strip sufficiently taut to insure the strip to be severed at the successive lines of perforations to afford a perfect transfer.

As the parts return to normal, the upward swing of the links or toggle bars 177—178, project the hook of the arm 184, over the toggle arm again for the next succeeding 105 operation, the trip bar swings back to normal to be arrested by the stop pin 172, and the inclined tail of the pivoted arm 173, retracting the finger 174, from the notch in the ratchet wheel, and this occurs simultaneously with the head 188, of the leaf spring 187, again falling into the notch at the lower side of the ratchet wheel to hold the mechanism from further movement. The pawl 180, again projects over and into 110 engagement with the finger 174, ready for the next succeeding movement. Conveniently, a comb is suitably mounted between the frame plates to bear against the transfer strip as it feeds upwardly over the roll 120 15, and to direct the apertures therein upon the pins 16. A corresponding comb 191, is provided at the upper inner side of the roll and the thin wedge shaped teeth thereof rest upon the periphery of the strip feeding roll to strip the same from the pins 16, of the roll and prevent injury to the strip.

Preferably, a resilient deflector 192, is suitably supported upon a rod 193, extending transversely the machine and with its 130

free end directed toward the printing ribbon and acts to deflect the strip downwardly and sufficiently to permit the same to pass beneath the inked ribbon without contacting the same normally, thus avoiding the inking or soiling of the strip by drawing the same across the ribbon.

For the purpose of adjusting the upward throw of the printing frame, a strong bar 194, is secured transversely the frame and engages at its ends to the frame plates 6 and 7, and an adjusting screw bolt 195, is set therein with the head thereof to bear against the leaf spring 136, the adjustment 10 of said bolts enabling the tension of the spring at the time of release to be adjusted to suit the requirements of the machine. A recoil spring 196, and, as shown, a leaf spring, as shown in Fig. 25, is secured on the 20 frame plate 6, and bears over the gudgeon 140, and is sufficiently strong to prevent a second upward throw of the printing frame after the first impression.

As shown also, a hook 197, is pivotally supported upon the frame plate 6, in position to engage the gudgeon 140, when the printing frame is depressed, thus enabling the printing frame to be held down during adjustment or repair. Preferably, shaft 18^a, 25 for the ejecting rolls, is yieldingly mounted. For this purpose, the aperture in the frame plates for said shaft is sufficiently enlarged to afford the desired clearance and an arm 198, as shown in Figs. 27 and 37, is pivoted 30 to the frame plates 6 and 7, at the inner side of each and the ends of the shaft 18^a, are journaled in one end of each. The upper end of each is engaged by a weak pulling spring 199, the other end of which is engaged by the respective frame plates to maintain a light tension at all times on said roll.

Inasmuch as the minute printing wheel is marked for intervals of three minutes, it is desirable to afford mechanism whereby the 45 minute wheel will be properly adjusted at the nearest three minute interval. For this purpose, as shown, a crank 200, is pivotally supported in the frame plate 7, above the tripping bar, with the crank arm thereof to 50 be projected into position to be engaged by the end of the tripping bar when it returns to normal, and to be swung inwardly thereby.

Rigidly secured on the crank 200, at the 55 inner side of the plate, is an upwardly extending link or arm 201, at the upper end of which is engaged a thrust rod 202, as shown in Fig. 11, which extends inwardly with the end thereof bearing upon the minute ratchet wheel. A pulling spring 203, engages said thrust bar 202, and is engaged at any suitable fixed point at its other end to draw said thrust bar inwardly when the crank arm is released. In consequence, when 60 the tripping bar is actuated and the crank

200, is released, said spring acts to pull the thrust bar inwardly, returning the minute printing wheel to the nearest three minute interval on the printing wheel, the adjustment being limited, as indicated in Fig. 11, 70 by the lower pawl 61, which stops the minute printing wheel at exactly printing position. This reverse movement is made possible by the yielding engagement of the gear wheel 124, for the minute printing wheel on 75 its shaft, as indicated in Figs. 6 and 36. Of course, with the return of the tripping bar to normal, the crank is engaged thereby, as shown in Fig. 6, and swung to position to again retract the thrust bar. 80

An external or any visible counter may be actuated to indicate the number of transfers that have been delivered from the machine, and for this purpose the counter 204, is mounted at any convenient point to enable the same to be inspected readily and the shaft 205, thereof is provided with an arm 206, and a connecting rod 207, engages said arm with a wrist pin 207, on a pulley or wheel 208, which is secured on the end 85 of the shaft 144. In consequence, each actuation of the shaft acts to register one upon the counter. 90

It is of course, to be understood that we have shown and described but a preferred 95 form of our invention. Numerous details of construction and operation may be varied without departing from the principles of our invention, and we do not purpose limiting the patent otherwise than necessitated 100 by the prior art.

We claim as our invention:

1. A transfer printing and issuing machine, embracing a transfer strip, continuously acting timing and dating means 105 constituting a printing element, an inked ribbon fed transversely of the transfer strip between the same and said printing means, means to impel the transfer strip and inked ribbon against the printing means, intermittent feed mechanism for the transfer strip and the inked ribbon, and a knife acting to sever the printed transfer from the strip when the printing is completed. 110

2. In a transfer printing and issuing machine, a printing, timing and dating mechanism, means for feeding a transfer strip thereto for printing, a knife positioned beyond the printing means, a counter, mechanism acting intermittently to advance the 115 transfer strip a distance equal to the width of one transfer, an actuating lever, operative connections between the same and the advancing printing and severing mechanism, and operative connections between said lever 120 and the counter whereby each transfer issued is counted thereon. 125

3. In a transfer printing and issuing machine, a printing element, means for feeding a transfer strip thereto for printing, an 130

- inked ribbon disposed transversely of the transfer strip between the same and said printing means, means operated by the transfer feed means for feeding said ribbon, 5 means for automatically reversing the direction of feed of said ribbon when it reaches each end of said feed, and a knife acting to sever the printed transfer from the strip when the printing is completed.
- 10 4. In a transfer printing and issuing machine, a transfer strip, a printing element, an inked ribbon fed transversely of said strip between the same and said printing element, means to impel said strip and ribbon 15 against the printing element, intermittent feed mechanism for said strip and ribbon comprising a cam, mechanism intermediate said cam and ribbon and operated by said cam for reversing the application of the 20 power to said ribbon, and a knife acting to sever the printed transfer from the strip when the printing is completed.
5. A transfer printing and issuing machine, embracing a transfer strip, a printing 25 element, an inked ribbon fed between said strip and said printing element, means to impel said strip and ribbon against said printing element, feed mechanism for said strip and ribbon comprising an eccentric 30 for imparting a step-by-step motion to the ribbon feed, and means controlled by the ribbon spools for varying the length of the connection between said eccentric and the ribbon spool operating mechanism to reverse 35 the direction of operation of the latter.
6. A transfer printing and issuing machine, embracing a transfer strip, a printing element, an inked ribbon fed between said strip and said printing element, means 40 to impel said strip and ribbon against said printing element, feed mechanism for said strip and ribbon comprising an eccentric for imparting a step-by-step motion to the ribbon feed, an eccentric rod operated thereby, a 45 bar connected with the ribbon spool operating mechanism, and retained in shiftable re-
- lation to said rod, a spring for retaining said rod and bar in either extreme of adjustment, and means operated by either of the ribbon spools when empty for shifting said rod 50 relatively to said bar and thereby to reverse the ribbon feed.
7. In a printing and issuing machine, printing mechanism, a clock connected thereto to properly to set the same for the year, 55 month, day, hour and minute, including the month of February for leap years, means for delivering a continuous strip of blank transfers into said printing mechanism, mechanism independent of said delivering means 60 for ejecting the same positively therefrom, and a knife actuated by the recoil of a spring to sever said continuous strip after portions thereof have been printed.
8. In a printing and issuing machine, a 65 strip roll, a feed roll adapted to draw the strip therefrom, printing mechanism adapted to receive the strip from said feed roll, delivery mechanism independent of said feed roll adapted to eject the strip from said 70 printing mechanism, a knife adapted to sever the printed portion of said strip, a lever pivotally mounted on said device, a strong spring normally retaining the same in retracted position, a shaft journaled in said 75 device, bevel gears thereon, one to drive said feed roll and another to drive the delivery mechanism, a ratchet wheel journaled adjacent said shaft, a bevel gear connected to said ratchet wheel and meshing with one 80 of the bevel gears on said shaft to drive said shaft, and pawl mechanism adapted to actuate said ratchet wheel and connected for movement to said pivoted lever.
- In testimony whereof we have hereunto 85 subscribed our names in the presence of two subscribing witnesses.
- ROBERT B. CRAIG.
ALBERT L. COFFMAN.
